PROCESS FOR RECOVERY OF AROMATICS
SEPARATED FROM CYCLIC DIENES

Glen P. Hamner, Baton Rouge, La., assignor to Esso Research and Engineering Company, a corporation of Delaware

Application September 7, 1951, Serial No. 245,563

6 Claims. (Cl. 260—674)

The present invention has to do with recovery of aromatic fractions suitable for preparation of pure benzene and pure toluene with separation of interpolymerized diolefins therefrom following segregation of valuable C₅ diolefinic components.

Hydrocarbon streams from high-temperature vapor-phase cracking of petroleum contain largely olefins, diolefins, and aromatic hydrocarbons with relatively small amount of paraffins.

In addition to cyclopentadiene and methyl cyclopentadiene there are other cyclic diolefins and conjugated open-chain diolefins of higher molecular weight which tend to distill together with benzene and toluene from the hydrocarbon streams containing these compounds, despite various efforts to remove the diolefins by simple or drastic steps from a narrow boiling fraction of the high-temperature vapor-phase cracked petroleum products.

The high-temperature vapor-phase cracking processes have already been described in the prior art and need not be more fully discussed. In these high temperature cracking processes, naphtha through gas oil boiling range petroleum fractions, boiling in the range of 250° to 700° F., are cracked in the vapor phase at 1000° F. to 1600° F. in a short period of about 1 to 5 seconds under low pressures of about 1 to 10 atmospheres, and in the presence of steam amounting to about 50 to 90 mole per cent based on the hydrocarbon feed. A process of this type is described in U. S. Patent 2,363,903, patented November 28, 1944, by B. I. Smith, and U. S. Patent 2,348,659, patented May 9, 1944, by B. I. Smith et al.

The patents relating to the vapor-phase cracking also describe certain methods of recovering low-boiling fractions up to and including a butadiene-containing fraction and recovering the higher fractions from the highly cracked products.

The present invention is concerned more particularly with recovery of other individual valuable higher-boiling C₅ to C₇ compounds and polymer products in an efficient manner. These higher-boiling valuable hydrocarbons include such substances as isoprene, cyclopentadiene, methyl cyclopentadiene, benzene, and toluene mixed with C₅—diolefins, dimethyl cyclopentadiene, ethyl cyclopentadiene, and desired polymers of the diolefins.

It has been found in reducing the present invention to practice that for improved recovery of each of the individual types of products, certain precautions have to be taken during the separation steps to prevent undesired polymerization reactions and decomposition reactions while segregating the various components, otherwise the recovery of the desired final substances in high purity and good yield is adversely affected.

According to the present invention, final benzene and toluene concentrates suitable for purification, for example, by known methods of extractive distillation, are obtained from two or more separately processed cracked distillate streams: the first or lightest stream being richest in C₅—C₆ hydrocarbons, the second or intermediate boiling range stream being richest in C₇—(C₇ and higher)

2

hydrocarbons, and a third stream is richest in C₈—(C₈ and higher) hydrocarbons. The separate treatment of each of such streams from a high temperature vapor phase cracking process will be discussed in greater detail with reference to the flow plan of the accompanying drawing.

(1) *The C₅—C₆ rich stream.*—This stream contains 20—25 weight percent C₅, 40—50 weight percent C₆, and 25—25 weight percent C₇ hydrocarbons with some dimerized C₅—C₆ cyclo-dienes and negligible amounts of C₄ hydrocarbons.

Referring to the flow plan in the drawing, the C₅—C₆ rich fraction passed as the lightest stream through line 1 is first thermally soaked at a temperature of 200°—220° F. for 4 to 8 hours in a soaking zone S-1 for selective and practically complete dimerization of cyclopentadiene and methyl cyclopentadiene present in such a fraction. The dimerization selectivity approaches 100% when the suitable conditions of the order mentioned are used for selectively dimerizing the C₅—C₆ cyclodienes without polymerizing other diolefins present in this fraction.

The dimerized C₅—C₆ rich fraction is fed from the soaking zone S-1 through line 1A to a fractionating column A. An overhead fraction boiling in the range of about 60° F. to 300° F. is removed overhead from column A as a distillate stream through line 4. The C₅—C₆ cyclodienes are recovered to the extent of 90—95% as dimers in the bottoms of column A and removed through line 5. The bottoms temperature of column A should not exceed 280° F. to avoid undesired depolymerization of the dimers while separating the other type of hydrocarbons from the dimers. For optimum operation, pressures of 5 to 10 p. s. i. g. and temperatures from 185° F. to 260° or 240° F. are maintained from top to bottom in column A.

The overhead distillate from column A contains C₅—C₇ hydrocarbons from which about 15 weight percent of the feed to this column is obtained as the dimer bottoms product. The C₅ hydrocarbons include 15—20 weight percent isoprene, 10—15 weight percent piperylene, 15—20 weight percent tertiary alkenes, 40—45 weight percent non-tertiary alkenes and less than 5% paraffins. The C₆ hydrocarbons include 15—20 weight percent dienes, 10—15 weight percent tertiary alkenes, 40—45 weight percent benzene, 20—25 weight percent non-tertiary alkenes, and less than 3 weight percent paraffins. The C₇ hydrocarbons are similar to the C₆ hydrocarbons in type and proportions except that toluene is 40—45 weight percent of the C₇ components.

(2) *C₇—rich stream.*—This stream contains about 2—3 weight percent C₅, 10—15 weight percent C₆, and 80—85 weight percent C₇—with relatively minor amounts of higher hydrocarbons above C₁₃. This stream is fed by line 2 to fractionating column B. An overhead distillate stream boiling up to 149° F. is removed by line 6 from column B and advantageously sent to the soaker S-1 for separation of additional C₅—C₆ components. An intermediate fraction of side stream boiling mainly in the range of 149°—185° F. is withdrawn through line 7 from column B. This intermediate fraction is close cut and contains about 45—50 weight percent benzene, 15—20 weight percent dienes including cyclodiene monomers since this fraction has not been thermally soaked, 10—15 weight percent tertiary alkenes, 15—20 weight percent non-tertiary alkenes, 5—10 weight percent cyclopentenes, and less than 3 weight percent paraffins. The bottoms or residual product of column B removed by line 8 is 185° F. and higher-boiling material that need not be further treated for recovery of selected hydrocarbons. Pressures of 15 to 20 p. s. i. g. and a bottoms temperature of 350° F. are suitably maintained in column B.

(3) *The C₈+* rich stream.—This stream contains approximately 20–25 weight percent C₇ hydrocarbons, and 70–80 weight percent C₈+ hydrocarbons including a minor amount of hydrocarbons heavier than C₁₃. This stream is passed by line 3 to be fractionated in column C so that substantially all its toluene content is distilled overhead to be removed by line 9 as a C₇ fraction boiling up to 250° F. The C₇ overhead distillate stream contains 10–15 weight percent dienes, 40–45 weight percent toluene, and 5 to 10 weight percent paraffins, the remainder being alkenes. The proportion of paraffins may be higher depending upon the type of petroleum naphtha cracked to obtain this stream. The residue or bottoms fraction in tower C is the 270° F. and heavier material withdrawn by line 10 for use in motor gasoline or other purposes. Pressure of 85 to 90 p. s. i. g. and a bottoms temperature of 435° F. are suitably maintained in column C.

The distillate stream removed by line 4 from tower A is fed to fractionating column D. Column D is operated to take overhead a C₅ fraction boiling up to 140° F. as stream 11 and to yield a bottoms C₆–C₇ rich fraction. Since distillate streams 7 and 9 from towers B and C respectively are substantially C₅-free, they are then combined, as a stream 12, with the bottom C₆–C₇ fraction withdrawn by line 13 from column D to form stream 14 which is fed to the second thermal soaker S-2. Pressures of 15 to 25 p. s. i. g. and a bottoms temperature of 260° F. are suitably maintained in column D.

The thermal soaker S-2 is a vessel in which the combined benzene and toluene rich fractions from the initial streams combined in line 13 are held under pressure at a more elevated soaking temperature than was used in the first soaking vessel S-1, e. g., being held under pressures of 100 to 400 p. s. i. g. at 220° F. to 400° F. for 6 to 8 hours. In this second soaker, C₆+ cyclodienes are polymerized and interpolymerized with open chain C₆+ diolefins, the olefinic hydrocarbons having 6 and more carbon atoms per molecule thus being more intensely polymerized.

The liquid containing the polymers formed in soaker S-2 is fed by line 15 into fractionating column E. Column E is operated to take overhead a distillate fraction boiling within the range of 140°–240° F. through line 16. The polymers of the cyclodienes and straight chain dimers are removed as a bottoms stream 17 from column E. The bottoms temperature of column E should not exceed 280° F. and should preferably be closer to 240° F. to avoid depolymerization of unstable polymers. The desired fractionation in column E may be accomplished with the aid of steam injected from line 18 or under vacuum. Pressures of 5 to 10 p. s. i. g. and temperatures in the range of 185° F. to 260° F. are suitably maintained in column E.

The overhead stream 11 from column D is a C₅ rich fraction suitable for recovery of isoprene by extractive distillation, a piperylene concentrate, and other C₅ products. The recovery of these C₅ products may be carried out with the use of known extractive processes, such as employ an aqueous acetone solvent.

The benzene- and toluene-rich distillate stream 16 taken overhead from column E is satisfactorily free of reactive diolefins hydrocarbons that are undesirable sludge forming substances in subsequent extractive distillation treatments used for recovery of benzene and toluene of high purity, for example, extractive distillation with phenols, furfural, or triethylene glycol. Furthermore, by the separation steps used in obtaining the benzene and toluene distillate from column E there is very little loss of benzene or toluene from the amounts initially available in the initial crude cracked products.

A highly important advantage is gained through the use of the two separate polymerization operations that permit recovery of a valuable cyclopentadiene dimer product (in stream 5 from column A), a good recovery

of isoprene and piperylene in stream 11 from column D, and finally a removal of reactive diolefins hydrocarbons as a polymer product (in bottom stream 17 from column E).

Tests were conducted to determine the efficiency of the operation described for yielding benzene and toluene concentrates suitable for purification by extractive distillation with phenol. The results of these tests indicated that thermal soaking at elevated temperatures of a C₆–C₇ stream is as efficient as clay treatment at similar temperatures for removing sludge-forming diolefins. In comparative tests, separate portions of the C₆–C₇ fractions were treated at about 300° F. by thermal soaking as prescribed for zone S-2 and by clay. The treated materials were fractionated to obtain a 185°–240° F. toluene fraction distilled away from the polymers and the toluene fractions were contacted with phenol under extractive distillation conditions of 350° F. for three hours.

Tests have demonstrated that polymers of the C₅ and C₆ cyclodienes and of some other diolefins close-boiling thereto are the polymers which are most susceptible to depolymerization under conditions of fractionally distilling the benzene and toluene concentrates; therefore, there is a certain advantage gained by eliminating the C₅ and C₆ cyclodienes by dimerization and eliminating C₅ acyclic diolefins by distillation from stream 1 in which they are mainly present before the combined distillation C₆–C₇ rich fractions of the several streams are subjected to the higher temperature second stage polymerization to form more stable polymers from remaining C₆–C₇ diolefins.

Attention is called to the fact that in the described process, only one of the initial streams need have all its components encounter polymerization conditions in the first soaker S-1. The lowest boiling stream 1 which is richest in C₅ and C₆ hydrocarbons first becomes subjected to the selective thermal polymerization in the polymerization vessel S-1. Some of the components of this stream after removal of cyclodiene dimers in fractionator A and removal of C₅ distillate from fractionator D are subjected to the non-selective polymerization in the second polymerization vessel S-2. On the other hand, certain distillate fractions from the second and third streams that reach the second polymerization vessel S-2 need not be subjected previously to a selective thermal polymerization (cyclodiene dimerization).

Since the polymerization which is effected in the second polymerization vessel S-2 is intended to be far-reaching or more drastic in polymerizing as much of the acyclic C₆–C₇ diolefins as possible at elevated temperatures; this non-selective polymerization in S-2 may be carried out with the aid of polymerizing catalysts, such as activated or mineral acid treated clay, at temperatures of the order of 220° F. to 400° F. and under pressures sufficiently high to maintain the hydrocarbons undergoing treatment in the liquid phase, e. g., 100 to 400 p. s. i. g.

Although the operations have been described in detail with regard to treatments of three initial separate streams; a C₅–C₆ rich stream (1), a C₇+ rich stream (2), and a C₈+ rich stream (3), an important factor of the operations involve the treatments of principally streams (1) and (2).

In the treatments of streams (1) and (2), it is particularly desirable to avoid having a high concentration of diolefins that are close-boiling to benzene, such as in stream (2), mixed with the material of stream (1) which is subjected to the selective polymerization or cyclic diolefin dimerization in vessel S-1. It is beneficial for the quality of the dimer product withdrawn by line 5 from column A, for the separation of a suitable C₅ cut withdrawn overhead from column D, and for the quality of the polymer product withdrawn from column E by line 17, if C₅ and higher diolefins hydrocarbons boiling above 140° F. are diverted to the polymerization zone

in vessel S-2 insofar as possible without carrying along thereto substantial amounts of C₅ hydrocarbons. The polymerization in vessel S-2 is controlled much better and in column E the polymer product is more stable if the C₅ hydrocarbons have been largely eliminated from the mixed feed streams to the vessel S-2.

The lightest stream (1) may contain varied proportions of C₅ and C₆ components but its components should be mostly lower boiling than C₇ hydrocarbons for improved separation of cyclic diolefin dimers in column A following the thermal dimerization. The next higher boiling stream (2) thus will contain mostly hydrocarbons higher boiling than C₇ hydrocarbons if separated from stream (1) by ordinary fractional distillation of a cracked naphtha.

What is claimed is:

1. In a process of separating C₅ and C₆ cyclic diolefins, C₅ acyclic diolefins, benzene and heat stable polymers of diolefins from vapor-phase cracked naphtha fractions containing C₅ to C₇+ cyclic and acyclic diolefins with benzene, the steps of thermally soaking a C₅-C₆ rich fraction to dimerize C₅ and C₆ cyclic diolefins therein, distilling remaining unreacted C₅ and C₆ hydrocarbons from the dimerized cyclic diolefins, separating C₅ acyclic diolefins from the resulting C₅-C₆ rich distillate which is distilled from the dimerized cyclic diolefins, subjecting the remaining C₅ to C₆ fraction thus freed of cyclic and acyclic C₅ diolefins to more intense second polymerization than said thermal soaking to form stable polymers of remaining cyclic and acyclic diolefins, and distilling benzene from resulting stable polymers of said second polymerization.

2. In a process of separating C₅ to C₆ cyclic and acyclic diolefins from a C₅-C₆ rich hydrocarbon mixture containing said diolefins with mainly C₅ to C₆ mono-olefins and benzene, the improvement which comprises selectively dimerizing C₅ and C₆ cyclic diolefins in said mixture by thermally soaking said mixture in liquid phase at a temperature of about 200 to 220° F., then separating the remaining unreacted diolefins, mono-olefins and benzene components of said mixture as a distillate from the dimerized cyclic diolefins, fractionally distilling from said distillate C₅ acyclic diolefins to obtain a residual fraction containing C₆ acyclic diolefins, mono-olefins and benzene, polymerizing principally the diolefins in said residual fraction freed of the dimerized cyclic diolefins and of C₅ acyclic diolefins to stable polymers which are more heat stable than the dimerized cyclic diolefins, and distilling from the said residual fraction, containing the stable polymers, the benzene with the mono-olefins left unreacted.

3. In a process of separating C₅ to C₆ cyclic and acyclic diolefins from a C₅-C₆ hydrocarbon rich mixture containing said diolefins with C₅ to C₆ mono-olefins and aromatic hydrocarbons, the process which comprises first selectively dimerizing C₅ and C₆ cyclic diolefins in the C₅ to C₆ rich mixture by mild thermal dimerization, then separating as a distillate the remaining unreacted C₅-C₆ diolefins, mono-olefins and aromatic hydrocarbons from the resulting dimerized cyclic diolefins in a fractional distillation zone in which temperatures are prevented from exceeding 280° F. to avoid undesired depolymerization of the dimers and undesired polymerization of acyclic diolefins, subsequently passing said distillate from the first fractional distillation zone into a second fractional distillation zone, distilling in said second fractional distillation zone C₅ acyclic diolefins to yield a bottoms C₆ rich fraction containing benzene, mono-olefins, and acyclic diolefins which form polymers when thermally polymerized at temperatures above 220° F., said bottoms C₆-rich fraction being thus substantially freed of C₅ diolefins polymerizing principally the C₆ diolefins in said bottoms fraction removed from second fractional distillation zone to form heat stable polymers therefrom, then distilling the C₆ mono-olefins and ben-

zene from the said thermally stable polymers of the C₆ acyclic diolefins.

4. In the process of recovering diolefinic and aromatic hydrocarbon products of value from a cracked petroleum, the steps which comprise treating cracked naphtha hydrocarbons in separate streams: (1) a C₅-C₆ rich stream, (2) a C₇+ rich stream, and (3) a C₈+ rich stream; thermally soaking the C₆ rich stream (1) at mild dimerizing temperatures in the range of 200-220° F. to dimerize C₅-C₆ cyclodienes therein, and separating a remaining C₅-C₆ rich distillate from the resulting dimers; fractionally distilling from the C₇+ rich stream (2) a narrow benzene-rich distillate fraction boiling in the range of 149°-185° F., distilling from the C₈+ rich stream (3) a lightest C₇ rich distillate; fractionally distilling from said C₅-C₆ rich distillate from stream (1) after separating the dimers of C₅-C₆ cyclodienes its C₅ hydrocarbon components boiling up to 140° F. to obtain a residual fraction rich in C₆ and C₇ hydrocarbons; combining said C₅-C₇ rich residual fraction from stream (1) with the benzene rich intermediate distillate fraction of stream (2) and the lightest C₇ distillate fraction of stream (3); subjecting said combined fractions to temperature in the range of 220° F.-440° F. until substantially all cyclodiene components and open chain diolefins of this fraction undergo polymerization; then fractionally distilling unpolymerized hydrocarbon components of the thus treated combined fractions to distill benzene and toluene away from a residual polymer product.
5. In a process of separating C₅ diolefins and C₆-C₇ aromatic hydrocarbons from a cracked petroleum naphtha, the steps which comprise treating the cracked petroleum naphtha in at least two separate streams: (1) a C₅-C₆ rich stream and (2) a C₇ rich stream; thermally soaking the C₅-C₆ rich stream at mild dimerizing temperatures in the range of 200°-220 F. to dimerize C₅-C₆ cyclodienes therein; separating the remaining unreacted hydrocarbons of the C₅-C₆ rich stream (1) from the resulting dimers by distillation therefrom; then fractionally distilling from the unreacted hydrocarbons of the C₅-C₆ rich stream hydrocarbon components boiling up to 140° F. to obtain a residual C₆-C₇ fraction rich in benzene; fractionally distilling from the C₇+ rich stream (2) a narrow benzene-rich distillate fraction boiling in the range of 149°-185° F.; combining the residual C₆-C₇ rich stream fraction free of components which boil up to 140° F. and free of the cyclodiene dimers with said benzene-rich distillate fraction from the C₇+ rich stream (2); passing said combined fractions rich in benzene into a polymerization zone; maintaining said combined fractions rich in benzene at temperatures in the range of 220° F.-400° F. until substantially all C₆-C₇ diolefins in said combined fractions undergo polymerization; then passing a resulting hydrocarbon mixture rich in benzene and polymers formed from the polymerization zone into a fractional distillation zone; and distilling benzene with close-boiling hydrocarbons from the polymers in said fractional distillation zone.
6. In a process of recovering diolefinic and aromatic products from a vapor-phase cracked petroleum naphtha, the steps which comprise separating the cracked petroleum naphtha into three separate streams: (1) a C₅-C₆ rich hydrocarbon stream containing isoprene, cyclopentadiene, benzene and methyl cyclopentadiene; (2) a C₇+ rich stream and (3) a C₈+ rich stream; thermally soaking the C₆ rich stream at mild dimerizing temperatures in a range of 200°-220° F. to dimerize C₅-C₆ cyclodienes; fractionally distilling from unreacted hydrocarbons of the C₆ rich stream hydrocarbon components boiling up to 140° F. to obtain a residual fraction rich in benzene; fractionally distilling from the C₇ rich stream (2) a narrow benzene-rich distillate fraction boiling in the range of 149° F. to 185° F.; distilling from the C₈+ rich stream a narrow toluene-rich distillate fraction boiling in the range of 200-240° F.; combining said fractions rich

in benzene and toluene from each of the three streams; passing said combined fractions rich in C₆ and C₇ hydrocarbons into a polymerization zone wherein diolefinic components thereof undergo polymerization at temperatures in the range of 220° F. to 400° F.; removing the 5 unpolymerized hydrocarbons together with polymers from said polymerization zone to a fractional distillation zone; and fractionally distilling unpolymerized C₆ and C₇ hydrocarbons from the polymers formed in said polymerization zone.
